STOKING MECHANISM

Edward Ryan, Knox, Ind., and Ernest R. Funk, Galesburg, Ill., assignors to The Standard Stoker Company, Incorporated, New York, N. Y., a corporation of Delaware

Application November 24, 1928, Serial No. 321,541
Renewed November 3, 1934

6 Claims. (Cl. 110—101)

The invention relates generally to stoking mechanisms and more particularly to a new and improved stoking mechanism especially adapted for use on locomotives having a wide grate.

5 It is the general object of the invention to provide an improved stoking mechanism adapted to distribute the fuel uniformly on a wide grate and intermittently to the opposite sides thereof.

It is another object of the invention to provide 10 such an improved mechanism embodying means for delivering the fuel to the fire box through two laterally spaced conduits.

Another object of the invention is to provide 15 an improved stoking mechanism embodying novel means for firing the two sides of the grate alternately and intermittently.

Another object of the invention is to provide a 20 stoking mechanism embodying a pair of downwardly extending distributing conduits through which the fuel is delivered into the fire box, a single screw conveyor for elevating fuel to said conduits, a distributing nozzle for each conduit and means for distributing fuel from said conveyor to the conduits.

25 Another object of the invention is to provide such a stoking mechanism embodying a reciprocating member arranged to feed fuel alternately from said elevating conveyor to the conduits together with means for reciprocating said member.

Another object of the invention is to provide 30 a stoker embodying a slightly inclined screw conveyor for transporting the fuel from beneath the bin to an upwardly inclined screw conveyor 35 mounted on the locomotive and adapted to deliver fuel from its upper end into a conduit entering the fire box above the mud ring, and means for rotating the screws of said conveyors continuously during operation of the stoker.

40 Other objects and advantages will become apparent as the description proceeds.

In the drawings,

Fig. 1 is an elevational view partly in section through a stoking mechanism embodying the 45 invention in its preferred form, associated with the fuel bin and the rear part of the fire box of a tender and locomotive respectively.

Fig. 2 is a fragmentary elevational view taken 50 along the line 2—2 of Fig. 1.

Fig. 3 is a fragmentary vertical section taken along the line 3—3 of Fig. 1.

Fig. 4 is a fragmentary elevational view on an 55 enlarged scale, partly in section, of the alternate firing mechanism.

Fig. 5 is an enlarged fragmentary view of said mechanism taken along the line 5—5 of Fig. 4.

Fig. 6 is a plan view taken along the line 6—6 of Fig. 5.

Fig. 7 is a fragmentary view, partly in section, taken along the line 7—7 of Fig. 4 (on a reduced scale).

Fig. 8 is a longitudinal section on the line 8—8 of Fig. 5 with the steam outlet pipes shown diagrammatically to illustrate the arrangement of 10 the valve.

As illustrated in the drawings and particularly in Fig. 1, a tender 1 is shown coupled to a locomotive frame 2. A fuel bin 3 suitably mounted upon the tender is provided with a bottom having an elongated discharge opening 4 therein adapted to be closed by a plurality of slidable plates 5. An approximately horizontal casing 6 enclosing a feed screw 7 is positioned beneath the bin and is arranged to receive fuel from the bin 20 and to convey it forwardly, this casing at its forward end being connected to an upwardly inclined approximately vertical casing 8 enclosing a second feed screw 9. The casing 8 extends upwardly and forwardly from the forward end of 25 the casing 6 and at its upper end connects with a conduit which enters the rear wall 10 of the fire box 10^a of the locomotive above the mud ring. In the exemplary form, the casing 8 connects at its upper end with a divided conduit in 30 the form of a pair of distributing or discharge conduits or tubes 11 and 12 (Figs. 2, 5 and 7) which as illustrated herein, extend from opposite sides to the upper portion 8^a of the casing 8, downwardly and forwardly through laterally 35 spaced apertures 15 in the wall 10 of the fire box above the ring 63.

The invention contemplates that the screws 7 and 9, which screws are preferably driven continuously during operation of the stoker, from 40 a single prime mover, will deliver fuel to the upper portion of the casing 8 from where it may, if desired, be forced into the conduit entering the fire box by additional fuel fed by the screws and furthermore by means of a steam spraying mechanism as hereinafter more fully described. The invention contemplates also that mechanical means may be embodied for feeding fuel through the discharge conduits and to this end the portion 8^a of the casing is preferably rectangular 45 in form (Fig. 6) and has mounted therein for adjustment or reciprocatory movement transversely thereof a feeding or distributing member or deflector vane 16. This member, as hereinafter 50 more fully described, may be positioned station- 55

arily with respect to the casing 8^a in which instance it will serve as a parting vane and distribute the fuel fed by the screw 9 into the conduits 11 and 12, or the deflector member 16 may 5 be given a continuous reciprocatory movement by means of a mechanism such as that herein designated generally 17, for the purpose of feeding fuel alternately through the conduits 11 and 12.

10 In the exemplary embodiment of the invention as illustrated in the drawings, the horizontal conveyor casing 6 has a ball and socket connection 18 with a rearwardly extending portion 9^a of the upwardly extending conveyor casing 8, and at its 15 rear end the casing 6 is suspended from the bin structure by means of a pair of rods 19 (Fig. 3) having ball and socket connections 19^a at their upper ends with brackets 20 mounted on the bin supports and at the other ends with a cross bar 20 21 formed integrally with the casing 6. That portion of the casing 6 which is beneath the bin opening 4 is open above as shown in Fig. 3 and is provided with upwardly inclined side walls 22 having horizontally extending flanges 23 along 25 their upper edges. A sealing ring 24 is normally spring pressed downwardly by means of springs 25, into constant engagement with the side flanges 23 and end walls 23^a (Fig. 1) and has a telescopic connection with a downwardly extending rim 26 secured to the bottom 3^a of the bin 30 and surrounding the opening 4. As shown most 35 clearly in Fig. 3 the rim 26 has a beveled surface 27 underlying the bin bottom 3^a adjacent the opening 4 and the plates 5 having their side edges formed to a corresponding bevel 28. By this arrangement the bin bottom and the rim cooperate to form V-shaped guideways for the plates 5 and there is no tendency for the fuel to collect on the supporting surfaces 27 for the plates.

40 With the casing 6 suspended at its rear end from the bin structure the invention provides a prime mover 29 mounted on a bracket 29^a secured to the rear end of the casing, together with suitable reduction gearing in a housing 30 intermediate the prime mover and the feed screw 7 so that the rear end of the casing 6 supports the prime mover and intermediate connections. Preferably the upwardly extending feed screw 9 is driven from the same prime mover as by means of 45 a flexible shaft 31 driven at its rear end by the gearing in housing 30 and connected at its forward end by means of a universal connection 32, positioned adjacent the ball joint 18, to a short shaft 33 rotatably mounted in a gear casing 34 50 secured to the lower end of the conveyor casing 8. The forward end of the shaft 33 carries a bevel gear 35 which meshes with a gear 36 secured to the drive shaft 37 of the feed screw 9. Thus the casing 6 has a movable connection with the tender 55 to provide for articulation between the locomotive and tender. A baffle plate 38 surrounding the shaft 37 at the lower end of the casing 8 has its peripheral edge mounted between the casing 8 and the gear casing 34 and is adapted to prevent the passage of any fuel into the gear casing 34 60 from the casing 8, and a door 8^b is provided for access to the lower end of casing 8. It will be apparent with the prime mover 29 operating and with a plate 5 slid forwardly from the opening 4, fuel will pass downwardly through the uncovered portion of the opening and will be conveyed forwardly in the casing 6 to the casing 8 and thence upwardly in said casing from whence it will be fed into the discharge conduits either due to the 65 feeding action of the screw 9 alone or in addition 70 75

by means of the member 16 when power operated.

5 In order to discharge the fuel from the conduits 11 and 12 through the horizontal portions 13 and 14 thereof and into the fire box, the invention contemplates the provision of a pair of steam nozzles 39 of any preferred design, which nozzles are positioned at the rear ends of the portions 13 and 14.

10 The member 16 which the invention embodies for use either as a stationary distributing vane or as part of an intermittent or alternate firing mechanism is herein disclosed as being mounted on a reciprocatory bar 40 slidably supported in bearing portions 41 formed on opposite sides of the casing portion 8^a (Figs. 4 to 7). This rod is 15 mounted adjacent the forward edge of the casing as shown in Figs. 4 and 6 so as to permit the shaft 37 of the feed screw 9 to be extended upwardly through the top of the casing for the purpose of driving the reciprocating mechanism for the 20 member 16 and a steam control valve as herein-after more fully described. The member 16 is 25 herein disclosed as being somewhat rectangular in shape (Fig. 4) and as being positioned entirely on the forward side of the shaft 37. The conduits 11 and 12 are however, preferably narrower than the casing portion 8^a as shown in Figs. 1, 4 and 6, so that the member 16 is an effective means for distributing the fuel.

30 In order to reciprocate the member 16 for the purpose of delivering fuel intermittently and alternately to the conduits 11 and 12, thereby to fire the two sides of the grate alternately, the invention provides in its preferred form, a mechanical means driven from the upper end of 35 shaft 37. As disclosed herein, this means comprises a pin 42 mounted eccentrically on a cam disk 43 secured to the shaft 37. A rod 44, pivotally connected at one end to the pin 42 has a nut 46 threaded on its opposite end 45. The nut 40 is suitably mounted rotatably upon an upwardly extending portion of an angularly shaped member 47, the horizontal extending portion of which has a pivotal connection by means of a pin 48 45 with a bracket 49 secured to the outer end of the bar 40. Thus the eccentricity of the pin 42 on the cam disk 43 determines the stroke of the member 16 and by means of adjusting the nut 46 on the rod 44 the path of reciprocation of the member may be displaced laterally of the casing 8 so 50 as to vary relative the amounts of fuel delivered to the conduits 11 and 12.

55 In order to supply steam to the nozzles 39 at proper times for distributing the fuel when fed intermittently, a suitable valve 50 may be 60 provided having a steam inlet pipe 51, and outlet pipes 52, 53 leading to the two nozzles. The valve member 50^a of the valve 50 is provided with a stem 54, the outer end of which carries a roller 55 adapted to be engaged by the cam disk 43. This cam is so shaped that it actuates the valve 50 properly to admit steam to the nozzles in timed 65 relation with the reciprocation of the member 16. The spring 80 in the valve 50 maintains the roller 55 in engagement with the cam disc 43. In order to permit of simultaneous firing with the member 16 stationary, a pipe 56 is provided connecting the pipes 52 and 53, together with a valve 57 therein, so that by opening the valve 57 steam which passes through the valve 50 through either 70 pipe 52 or 53 is distributed to both nozzles 39.

75 The invention provides not only an improved mechanism insofar as the conveying and distributing of the fuel is concerned but includes also an improved means for delivering the fuel into 75

the fire box. In its exemplary form, this means serves to assist in the distribution of the fuel into the fire box and to protect the delivery conduits from injury because of the intense heat.

- 5 This means comprises hollow or water lagged baffle plates 58 extending from the upper edge of the conduit portions 13 and 14 and into the fire box 10 to assist in directing the discharge of the fuel downwardly onto the grate, and includes 10 combined baffle and distributing plates 59, also of hollow water lagged construction, extending from the lower edges of the conduit portions 13 and 14. The plates 59 are provided with downwardly inclined channels 60 arranged to permit 15 some of the fuel to be discharged therethrough onto the rear portion of the grate. Suitable water connections 61 and 62 may be provided between the plates 58 and 59 and the rear wall 10 of the locomotive for the purpose of passing 20 water through the plates to keep them sufficiently cool to avoid injury to the forward ends thereof which extend into the fire box.

It is believed apparent from the foregoing that the invention provides an improved stoking mechanism for wide grate locomotives arranged efficiently for operation either for simultaneous or intermittent firing. The provision of a single vertical screw conveyor in serial relation to the horizontal conveyor together with a pair of delivery conduits leading from the upper end of the vertical conveyor, and feeding means between the casing and conduits affords a simple and efficient mechanism for alternately firing the two sides of the grate. This mechanism is readily adjustable during the operation of the stoker to vary the distribution to the two sides of the grate.

It will also be apparent that with the intermittent firing mechanism inoperative, the invention provides an improved stoking mechanism embodying a vertical screw conveyor feeding into discharge conduits which enter the fire box above the mud ring 63 and thereby do not reduce the grate area. In connection with either method of operation, the provision of water lagged baffle plates projecting into the fire box from the delivery tubes aids in the efficient distribution of the fuel onto the grate and prevents injury to the plates from the intense heat. As illustrated in Fig. 2 the delivery conduit portions 13 and 14 are arranged to enter the fire box on a level with and intermediate the hand firing doors 64 and 65 but as will be apparent to those skilled in the art, the relative positions of the tubes 13 and 14 and the doors 64 and 65 may be modified to meet existing conditions.

We claim as our invention:

1. In a stoker, in combination with a firebox, a screw conveyor casing arranged to extend upwardly outside the rear wall of the fire box, a feed screw therein, a pair of discharge conduits connected to said casing and communicating with the firebox through the rear wall thereof, means cooperating with said feed screw to distribute the fuel as it is discharged from the upper end of the casing adjustable to vary the distribution to the opposite sides of the casing, and means imparting reciprocating movement to said first named means for alternately delivering fuel to one and then to the other of said discharge conduits.

2. A stoker having, in combination with a firebox, a conveyor casing extending substantially parallel to and upwardly along the outer side of the fire box, a feed screw in said casing,

means for continuously operating said screw during the operation of the stoker, means for feeding fuel from a bin to the lower end of said casing, a pair of discharge conduits connected to said casing adjacent its upper end and communicating with the fire box, a distributing vane in the upper end of said casing, means for supporting said vane arranged to permit reciprocatory movement of the vane transversely of the casing and mechanism connected to the feed screw shaft arranged to reciprocate said vane for feeding fuel alternately to said conduits.

3. In combination with a firebox having an upstanding wall, a stoker conveyor casing arranged to extend upwardly along said wall, means in said casing for delivering fuel to an upper portion thereof, a divided delivery conduit having parts extending from the upper end of said casing arranged to communicate with horizontally spaced apertures in the fire box wall, a member movable transversely of and within the upper end of the casing, means imparting reciprocating motion to said movable member to deliver fuel alternately to the parts of said conduit, and adjustable means for varying the limits of the transverse movement of said movable member.

4. A locomotive stoker having, in combination, with a locomotive fire box, a conveyor casing extending upwardly along the rear wall of the fire box, a feed screw in said casing having a shaft projecting upwardly through the top of the casing, a pair of delivery conduits extending from the upper end of the casing to the firebox, means in the upper end of said casing arranged to direct fuel alternately into said delivery conduits and means operatively connected with the upper end of said shaft for operating said first named means.

5. A stoker having, in combination with a firebox, a conveyor casing arranged to extend upwardly along the wall of the fire box, a feed screw in said casing having a shaft projecting upwardly through the top of the casing, a pair of delivery conduits extending from an upper portion of the casing and arranged to communicate with the fire box, means in the upper end of said casing arranged to direct fuel alternately to said conduits, means operatively connected with the upper end of said shaft for operating said first named means, a pair of steam nozzles associated with said conduits for discharging the fuel therefrom, a valve controlling the passage of steam to said nozzles alternately, and means to operate said valve having a driving connection with the upper end of said shaft.

6. A stoker, having in combination with a firebox, a fuel conveyor casing extending upwardly along the wall of the fire box, a pair of delivery conduits extending from the upper end of said casing to the fire box, and means for feeding fuel alternately through said conduits comprising a feed screw in said casing, a distributing vane in the upper end of said casing arranged for transverse reciprocatory movement for directing fuel alternately to one and then the other of said conduits, a pair of steam nozzles associated with said conduits and a valve controlling the passage of steam to said nozzles alternately, and means for operating said distributing vane.

EDWARD RYAN.
ERNEST R. FUNK.
